SPRING-SUSPENSION AND STEERABLE WHEEL ASSEMBLY FOR STRADDLE TRUCKS

Filed March 7, 1945

UNITED STATES PATENT OFFICE

2,415,928

SPRING-SUSPENSION AND STEERABLE-WHEEL ASSEMBLY FOR STRADDLE TRUCKS

Walter A. Barr, Orange Tush, Ind., assignor to
The Ross Carrier Company, Benton Harbor,
Mich., a corporation of Michigan

Application March 7, 1945; Serial No. 581,421

3 Claims. (Cl. 280—96.2)

1

The present invention pertains to certain structural advantages and functional betterments in the spring-suspension and steering-means of trucks and more particularly, but not necessarily exclusively, in straddle-trucks, such as those used in the transportation of lumber and other loads and known in the trade as straddle-trucks because they straddle their load.

One object of this invention is to provide increased ease of steering the truck because the total load of the carrier is supported on ball-bearings, the side thrusts from the steering links and wheels being carried on the same bearings.

Another aim of the invention is to provide a construction permitting approximately 360° of steering rotation of the carrying-wheels without interference from spring supports.

A further purpose of the invention is to supply a structure of this type wherein the supporting spring is completely assembled within the fork and can, therefore, be packed in grease or oil and be protected efficiently from corrosion and dirt and at the same time be thoroughly lubricated.

Moreover, in the new construction the operator's vision is not obscured by outside spring mechanism, a supplemental object of the invention being to supply a structure which eliminates a considerable number of parts heretofore believed to be necessary, thereby providing a much simpler, cleaner design in which the elements coact and cooperate with one another in a satisfactory and efficient manner to maintain the parts properly in place and to permit the construction to operate effectively and efficiently.

To enable those skilled in this art to understand a present preferred embodiment of the invention accomplishing the above-indicated objects of the invention, such a construction has been illustrated in the accompanying drawing, forming a part of this specification, and to which reference should be had in connection with the following detailed description, it being borne in mind that like parts of the structure have been supplied with the same reference characters in both of the views presented in the drawing.

In this drawing:

Figure 1 is a partial elevation of one of the corner constructions of the straddle-truck which supports its load and also constitutes steering-mechanism for one corner of the truck, the sprocket-wheel and chain drive for the corresponding carrying-wheel being shown fragmentarily, and

Figure 2 is an enlarged, fragmentary, central,

vertical section through a portion only of such structure.

Referring to this drawing, it will be noted that the appliance includes a round fork-sleeve 11, constituting a corner casting of the frame of the truck, on which a corner portion of the truck load is imposed, the lower open end of such sleeve being equipped, partially internally and partly externally, with a demountable bearing 12 slidably accommodating an inner fork-tube 13 longitudinally slotted along its two sides in register at 14, 14, the otherwise open top of the fork-sleeve 11 being provided with an annular cover 15 demountably fixed to the top of the sleeve by a suitable plurality of bolts 16, 16, the tube 13 extending up out of the sleeve through a central aperture of corresponding size in the cover, as is clearly illustrated.

The lower end of tube 13 is appropriately mounted on, and fixedly secured to, the carrying-wheel assembly 17, 21 in any approved manner, as by bolts 18 and welding, so that when the tube is turned in the fork-sleeve by appropriate steering-mechanism including an arm 20 forming part of the closure 10 fixed in any suitable manner to the top of tube 13, the wheel 21 and its steering means, designated as a whole by 19, including its sprocket-wheel and chain connection 19 illustrated fragmentarily, will be turned correspondingly to perform its portion of the steering action of the vehicle.

A coiled, load-supporting spring 22 is housed within the upright tube 13 and bears at its lower end on the wheel-assembly 17, 21, by which it is supported, a round bearing-member 23, of substantially the same size as the interior of the tube 13 in which it is located, pressing against the top end of spring 22 and having a downwardly-extended, round projection 24 protruding into the interior of the spring, as is clearly portrayed, such part 23 having a round horizontal opening 25 therethrough occupied by a cylindrical pin 26 of a length substantially the same as that of the interior diameter of the sleeve 11 and 45 extending outwardly in opposite directions through the tube slots 14, 14 with its projecting ends occupying opposite registered apertures 27, 27 in a round bearing-collar 28 between the tube and sleeve and having an internal diameter approximately the same as the external diameter of the tube 13 and having an outer diameter about the same as the inner diameter of the sleeve 11.

Between the bearing-collar 28 and the under-surface of the sleeve-cover 15 is a circular ball-bearing including an annular row of balls 29 be-

tween an outer, upper ball-race 31 in contact with the under-surface of the cover 15 and the inner cylindrical surface of the sleeve 11, and a lower inner companion ball-race 32 of approximately the same inner diameter as the outer diameter of the tube 13 on which it bears, said part 32 being also in contact with the upper face of the bearing-collar 28, the latter having an upstanding, circular marginal rib 33 overlapping the outer edge of the part 32, as shown.

Obviously as the load on the fork-sleeve 11 varies, the spring 22 will be compressed downwardly more or less, the fork-assembly outside of the tube, by reason of its sliding connection with the tube, occupying different positions lengthwise the latter depending upon the amount of its load, such relative longitudinal displacement of the parts being permitted by reason of the presence of the slots 14, 14 in the tube which allow the pin 26 to change its elevation in the tube.

Regardless of the load acting on the spring, the turning of the tube by the steering-mechanism 20 can be readily accomplished for steering the carrying-wheel, the tube being oscillatory in the two bearings 12 and 29.

Although not illustrated in the drawing, the fork-sleeve 11 may be completely filled with any suitable lubricant, solid if preferred, for efficient lubrication of the moving parts, all of which are effectively housed and protected in the sleeve.

An understanding of this construction and its mode of operation will readily convey to one skilled in the art the manner of attaining the several objects of the invention hereinabove set forth and in this connection it should be borne in mind that the invention, as defined hereinafter, is not necessarily limited and restricted to the exact and precise details of structure and that these may be modified within reasonable limits without departure from the heart and essence of the invention, and without the loss or sacrifice of any of its material benefits and advantages.

I claim:

1. In a straddle-truck spring-suspension including a fork-sleeve on, and supporting its portion of, the truck-frame, a fork-tube rotatable and slidale in said sleeve, a spring in said tube bearing at its lower end on a carrying-wheel assembly, means to impose the supported load on the upper end of the spring, and means to turn said tube in said sleeve to steer said wheel, the novel improvement in an upper bearing of said

tube including in combination a bearing-collar between said fork-sleeve and said fork-tube and oppositely apertured in register with opposite longitudinal slots through said fork-tube, a bearing-member inside of said tube with an opening therethrough in register with said tube-slots and bearing on the upper end of said spring, a cross-pin occupying the apertures of said bearing-collar, the slots of said tube and the opening through the bearing member, a cover on said fork-sleeve centrally apertured to accommodate said fork-tube and covering the annular space between said fork-sleeve and fork-tube, and a ball-bearing between said bearing-collar and said cover, whereby said tube may turn in said sleeve for steering and the load on said fork-sleeve is imposed on said spring through said ball-bearing, bearing-collar, cross-pin and bearing-member, these parts being free to move lengthwise of the tube by reason of the slots in the latter.

2. The novel improvement as set forth in claim 1, in which said ball-bearing has a lower inner race around said tube and an upper outer race against the under-surface of said cover and the inner surface of said fork-sleeve.

3. The novel improvement set forth in claim 1, in which said ball-bearing includes an upper outer race bearing against the under surface of said cover and the inner surface of said fork-sleeve, and a lower inner race around said fork-tube and of approximately the same inner diameter as the outer diameter of the tube on which it bears, said lower inner race being also in contact with the upper face of the bearing-collar, the latter having an upstanding circular marginal rib overlapping the outer edge of the lower inner race.
